(57) **CLAIM**

The ornamental design for an automobile console attachment, as shown and described.

DESCRIPTION

FIG. 1 is a perspective view of the automobile console attachment showing my new design;

FIG. 2 is a top plan view of the same;

FIG. 3 is a front elevational view of the same;

FIG. 4 is a left side view of the same;

FIG. 5 is a right side view of the same;

FIG. 6 is a rear elevational view of the same; and,

FIG. 7 is a bottom plan view of the same.

The dash-dot-dash line is included to show the boundary of the claim and forms no part of the claimed design.

The dash-dash broken line showing of portions of the automobile console attachment is included for the purpose of illustrating environmental structure and forms no part of the claimed design.

1 Claim, 5 Drawing Sheets
